UNITED STATES PATENT OFFICE.

E. DWIGHT KENDALL, OF NEW YORK, N. Y.

APPARATUS FOR NAPHTHALIZING GAS.

Specification of Letters Patent No. 31,720, dated March 19, 1861.

To all whom it may concern:

Be it known that I, E. DWIGHT KENDALL, of the city, county, and State of New York, have invented a new and Improved Apparatus for Carbonizing Illuminating-Gas; and I do hereby declare that the following is a full, clear, and exact description of the same, reference being had to the accompanying drawings, forming part of this specification,

10 in which—

Figure 1, is a vertical section of the apparatus. Fig. 2, is a horizontal section of the same.

Similar letters of reference indicate corresponding parts in both figures.

In the use of the various apparatus heretofore invented for furnishing a supply of vapor of naphtha or other liquid hydro-carbon to mingle with illuminating gas near the 20 burners for the increase of its illuminating power, much difficulty has been experienced from the varying volatility and character of the different hydro-carbon liquids used, and from the effects of variation in the temperature of the atmosphere.

My invention consists in a certain construction of the apparatus whereby I am enabled so to regulate the supply of vapor as to obviate all difficulty from the above 30 causes.

To enable others skilled in the art to make and use my invention I will proceed to describe its construction and operation.

The particular apparatus represented in 35 the drawing is more especially adapted for application in connection with a single burner but by a proper construction of the inlet and outlet to adapt them to a service or branch pipe an apparatus similar in all 40 other respects and of suitable size could be made to serve for all or any number of the burners in a dwelling house or room or for a number of burners in any place.

A. is a socket whose inlet *a*, is made to 45 connect with the service pipe or a branch thereof and whose outlet *b*, is made to receive the burner or to connect with a pipe leading to the burner or burners. From one side of this socket there branches off two 50 distinct passages *c*, and *d*, the lower one *c*, forming a communication between the inlet *a*, and the lower part of an upright cylinder B., and the upper one *d*, forming a communication between the upper part of the said 55 cylinder and the outlet *b*, which has no direct

communication with the inlet *a*, through the socket A. The lower passage *c*, is fitted with a three-way cock C. which is situated at the junction with the said passage, of a transverse passage *e*, which communicates with the upper passage *d*, and the said cock is so constructed that it may shut off the inlet *a*, wholly or partly from the lower part of the cylinder B. or from the transverse passage *e*, so that all the gas may be made to 60 pass through the cylinder or all through the passage *e*, without passing through the cylinder, or that a portion may pass in one direction and a portion in the other direction as indicated in Fig. 1, by arrows. 65

The passage *c*, does not communicate directly with the interior of the cylinder B. but with a hollow band *f*, which surrounds the cylinder and which communicates with the interior of the cylinder by numerous 70 small holes *g*, *g*, which distribute the gas evenly all around the cylinder. The said cylinder is open at the bottom which is tightly secured to the open top of the reservoir F. which contains the naphtha or other volatile 75 hydro-carbon liquid. In the center of the reservoir and cylinder B. there stands a much smaller cylinder D. whose purpose is to keep extended a tubular wick *h*, said cylinder being secured to the bottom of the reservoir 80 by a screw *i*, or other means, being entirely open at the top and having small openings *j*, *j*, in its sides near the bottom. The wick is closed at the top as shown at *h'*, in Fig. 1, to cover the open top of the cylinder D. 90 like a cap.

Between the cylinders B. and D. there is placed a concentric cylindrical slide E. much shorter than the cylinder D., said slide fitting loosely to the exterior of the wick, but 95 fitting snugly to the portion of the cylinder B. below the hollow band *f*, that portion of the cylinder being contracted as shown at *l*, *l*, in Fig. 1, so that while the slide fits it, room enough is left between the slide and the 100 upper part of its interior for the free passage of gas between them.

The slide has connected with it a rod *m*, passing through a stuffing box *n*, in the closed top of the cylinder outside of which it is 105 furnished with a knob to be laid hold of for the purpose of moving the slide up or down to uncover less or more of the upper portion of the wick.

When the cock C. is set to close the passage 110

e, to the passage *c*, and open the latter to the cylinder, the whole of the gas passes through the cylinder and in passing over and around the surface of the upper portion of the wick 5 which is left uncovered by the slide, it takes up in the form of vapor a quantity of the naphtha or other hydro-carbon liquid which is carried up the wick from the reservoir *F*. by capillary attraction. By raising the slide 10 *E*. and exposing a smaller quantity of the surface of the wick the gas is caused to take up a less quantity of vapor and by depressing the slide and exposing a larger quantity of wick the opposite effect is produced.

15 When too high a degree of carbonization would be produced by passing the whole of the gas through the cylinder *B*. the cock *C*. may be so set that two thirds, one half, one third, or any proportion of the whole quantity 20 of gas may pass through the cylinder to be naphthalized or carbonized, the remainder passing by the passage *e*, to the outlet passage *d*, without being carbonized, and the carbonized and uncarbonized portions of the

gas mixing in the passage *d*, between the 25 passage *e*, and the outlet *b*.

When it is not desired to pass any of the gas in contact with the hydro-carbon, the cock *C*. is set to shut the passage *c*, from the cylinder *B*. and open it only to the passage 30 *e*, which will cause the whole of the gas to pass by the passage *e*, to the outlet *b*, without entering the cylinder *B*.

What I claim as my invention and desire to secure by Letters Patent is—

The combination of the reservoir *E*. cylinders *B*. and *D*. or their equivalents, wick *h*, and slide *E*. the whole applied substantially as herein described in relation to each other and to the inlet *a*, from the supply or service 40 pipe, and the outlet *b*, to the burner or burners substantially as and for the purpose herein specified.

E. DWIGHT KENDALL.
